UNITED STATES PATENT OFFICE.

JAMES M. POORE, OF SPRING VALLEY, MINNESOTA.

SEEDER.

SPECIFICATION forming part of Letters Patent No. 567,359, dated September 8, 1896.

Application filed August 10, 1895. Serial No. 558,896. (No model.)

To all whom it may concern:

Be it known that I, JAMES M. POORE, a citizen of the United States, residing at Spring Valley, in the county of Fillmore and State 5 of Minnesota, have invented a new and useful Seeder, of which the following is a specification.

My invention relates to seeders or planters of the class in which seed is sown broadcast 10 and is covered by means of a harrow or similar device, the objects in view being to provide a simple, strong, and durable frame, to provide improved connections between a ground-wheel and the seeding devices, to provide simple and efficient means for discharging and spreading or broadcasting the seed, and, furthermore, to provide efficient means 15 for the connection of the frame of the seeder with the draft-bars of a harrow, smoother, or similar device.

Further objects and advantages of this invention will appear in the following description, and the novel features thereof will be particularly pointed out in the appended 25 claims.

In the drawings, Figure 1 is a plan view of a seeder constructed in accordance with my invention. Fig. 2 is a side view of the same. Fig. 3 is a front view, partly in section. Fig. 4 is a longitudinal section. Fig. 5 is an enlarged section on the line 5 5 of Fig. 1. Fig. 6 is a detail view of the mechanism for communicating motion from the ground-wheel to the longitudinal shaft. Figs. 7, 8, and 9 are 30 detail views showing different means for arranging the movable partitions in the seedbox. Fig. 10 is a detail view of the means for adjusting the feed-cylinders. Fig. 11 is a detail view of the universal joint with which 35 the longitudinal shaft is provided. Fig. 12 is a detail view of one of the supporting-arms and the clamp suspended thereon for connection to the draft-bars.

Similar numerals of reference indicate corresponding parts in all the figures of the drawings.

1 designates a seedbox having continuous front and rear walls and a floor provided at intervals with outlet-openings 2, and bolted 40 to the rear side of said box is an angle-bar 3 of cross-sectionally angular construction, which is curved rearwardly at its center from

the box to form an arch or segment 4. This arch or segment is spanned in rear of the box by a cross-brace 5, having a forwardly-extending arm or projection 6 bolted to the under side of the seedbox. 55

The floor of the seedbox preferably inclines downward in opposite directions toward each outlet-opening in order to direct 60 the seed toward said openings, and arranged at the centers of the intervals between the openings are movable partitions 7 to prevent the seed from moving toward and accumulating at one end of the seedbox. Said partitions are movable in order that they may be displaced to facilitate the emptying and cleaning of the box, and in the drawings I have illustrated several ways of mounting the partitions. In Fig. 7 each partition is hinged at 70 its rear edge to the rear side of the seedbox, as shown at 8, and is provided at its front edge with a hook or catch 9 to engage a suitable keeper on the front side of the box. In Fig. 8 the front and rear edges of the partitions are fitted in grooves 10, formed in the front and rear walls of the box, and in Fig. 9 the partitions are pivoted at their upper edges by means of forwardly and rearwardly 75 extending trunnions 11, seated in the upper 80 edges of the front and rear walls, the lower edges of the partitions being held in place by means of catches or hooks 12.

Extending rearwardly from the center brace 5, which forms a part of the hopper or seedbox frame, and pivotally connected to said part, is a pivotal frame 13, comprising contiguous angle-bars bolted together at intervals and separated at their rear ends to form a fork 14, in which is arranged a ground-wheel 15. The front end of this pivotal frame is provided with clips 16, connected to the brace 5, and in rear of said clips is a guide 17, which engages the horizontal flange of the arch 4. 90

The cross-sectionally angular bars or beams forming the pivotal frame are secured together with their vertical flanges at the outer sides of the frame and their horizontal flanges in contact at their inner edges, thus forming 100 beneath the frame a longitudinal space enclosed at its top and sides, through which extends a longitudinal shaft 18. This shaft is mounted at its front end in a bearing-box 95

19, at its rear end in a bearing-box 20, and at an intermediate point, contiguous to the point of separation of the beams comprising the frame, in a bearing-box 21. The bearing-box 5 19 is arranged beneath the cross-brace 5, and in rear of said bearing-box, and directly under the pivotal point of connection of the frame 13 with the hopper or seedbox frame, the shaft or spindle 18 is provided with a universal joint 22. This universal joint consists of cross-heads 23 and 24, carried, respectively, by the members of the shaft or spindle and mounted in perpendicularly-disposed bearings in the connected caps or plates 25, said caps or plates being secured together by means of bolts 26. This joint provides for the transmission of rotary motion from the rear to the front member of the shaft or spindle without interfering with the lateral 15 swinging movement of the pivotal frame 13.

The ground-wheel 15 is provided with a shaft or spindle 27, mounted in bearings 28, supported by the angle-beams, said shaft or spindle having a bevel-gear 29, and the shaft 25 or spindle 18 is provided in rear of the bearing-box 20 with a similar bevel-gear 30, which meshes with the gear 29.

Secured to the under side of the hopper or seedbox, and communicating, respectively, 30 with the outlet-openings 2 in the bottom thereof, are cups 31, provided with openings 32, which are preferably arranged in the lower rear sides of the cups, and extending axially through said cups is a seeder-shaft 33, which is connected by means of intermeshing gears 34 and 35 with the front end of the shaft or spindle 18. The seeder-shaft is provided at intervals corresponding with the intervals between the openings 2, and mounted, 35 respectively, in the cups 31, with feed-cylinders 36. Each feed-cylinder comprises a smooth-surfaced section 37, fitting snugly in the cup, and a ribbed or corrugated section 38, also adapted to fit in the cup, and so constructed as to carry seed received from the opening 2 to the opening 32 when the seeder-shaft is in motion. Hence when the corrugated sections of the feed-cylinders are opposite the openings in the hopper or seedbox 40 the seed is conveyed to and discharged through the openings 32; but by moving the seeder-shaft axially the solid or smooth-surfaced sections of the feed-cylinders are brought opposite said openings to close the latter and prevent the escape of seed. This 45 axial motion of the seeder-shaft is communicated thereto by means of a hand-lever 39, which is connected to a yoke 40, secured to the shaft, and in order to provide for continuous communication of motion from the shaft or spindle 18 to the shaft 33 the bevel-gear 34 on said shaft 33 is feathered and is held from lateral movement with the shaft by means of ears 41, disposed upon either side thereof.

60 Arranged below the plane of the outlet-openings 32 is a forwardly and downwardly inclined chute or broadcasting-plate 42, pro-

vided at its extremities with slotted brackets 43, secured by means of bolts 44 to ears 45, depending from the hopper or seedbox. Said 70 broadcasting-plate may be arranged in any desired angular position and may be projected more or less to the front, as may be necessary in the operation of the mechanism.

The means which I employ for securing the 75 hopper or seedbox frame to the draft-bars 46 of a harrow or similar device (not shown) consist of forwardly and downwardly inclined supporting-arms 47, bolted at their upper ends, as shown at 48, to the angle-bar 3, and 80 provided at their front ends with lateral extensions 49, upon which are fitted eyes 50, at the upper ends of clamps 51. These clamps are thus swiveled upon the extensions 49 of the supporting-arms and are held from displacement by means of keys 52, engaging suitable transverse openings in said extensions. The clamps are bifurcated, as shown at 53, to receive the draft-bars 46, and the extremities of the arms formed by the bifurcation are 85 connected by means of a clamping-bolt 54, which, when tightened, causes the contraction of the arms and the clamping of the parts at the desired adjustment. By means of the construction thus described the seeder mechanism 90 may be arranged in any desired position with relation to the hopper or other covering device which is employed in connection therewith. Lateral adjustment of the supporting-arms is provided for by means of series of openings 48^a in the flange of the beam 3 for engagement by the bolt 48.

In addition to the above mechanism I employ means for checking the seeding devices by throwing the gear 30 out of engagement 105 with the gear 29, said means including a hand-bar 55, slotted at its rear end, as at 57, and arranged in operative relation with a bracket 56, which supports a thumb-screw 58, engaging said slot. The gear 30 is provided with 110 a grooved collar 61, with which engages a sleeve 62 on the front end of the hand-bar 55, and the gear is mounted to slide upon a cross-sectionally angular portion 63 of the shaft 18. By moving the hand-bar forwardly and rearwardly the gear 30 may be disengaged from or engaged with the gear 29.

Arranged between the rear ends of the beams on the pivotal frame, in rear of the ground-wheel 15, is a cross-bar 59, carrying a 120 scraper 60.

Various changes in the form, proportion, and minor details of construction may be resorted to without departing from the spirit or sacrificing any of the advantages of the invention.

Having described my invention, what I claim is—

1. The combination with a hopper, seeding mechanism and means for operating the same, 130 of an adjustable broadcasting-plate arranged in the path of seed discharged from the hopper, slotted brackets secured to the distributing-plate and having their slots arranged par-

allel with the plane of the plate, and fixed bolts engaging said slots, the distributing-plate being capable of both angular and forward and rearward adjustment to cause it to 5 properly receive and broadcast the seed, substantially as specified.

2. The combination with a hopper and seed-discharging mechanism, and draft-bars, of supporting-arms secured to the hopper and 10 inclined downwardly toward their front ends, clamps removably fitted upon extensions of said supporting-arms, said clamps being bifurcated to form separated arms between which said draft-bars are arranged, and clamp-bolts for adjusting the free ends of the arms whereby the clamps may be secured to the draft-bars at the desired points, substantially as specified. 15

3. The combination with a hopper, of an angle-bar secured to the rear side thereof and having a rearwardly-bowed central portion forming an arch, a longitudinal frame pivoted concentric with said arch and provided with a guide engaging the arch, a ground-wheel mounted in bearings upon the longitudinal frame, seed-discharging mechanism coöperating with outlet-openings in the hopper, and connections between the ground-wheel and said discharging mechanism, substantially as specified. 25

4. The combination with a hopper and seed-discharging mechanism, of a longitudinal frame pivotally connected to the hopper and capable of a lateral swinging movement at 30 its rear end, said frame comprising angle-

beams separated at their rear ends, a ground-wheel mounted in bearings between the separated rear ends of said angle-beams, a shaft or spindle mounted in bearings upon and arranged parallel with said beams, connections 40 between the shaft or spindle and the ground-wheel, connections between the front end of the shaft or spindle and the seed-discharging mechanism, and a universal joint in the shaft or spindle contiguous to the pivotal point of 45 connection of the longitudinal frame with the hopper, substantially as specified.

5. The combination with a hopper, of a transverse angle-beam secured to the hopper and provided at its center with a rearwardly-extending arch, a cross-bar spanning said arch, a longitudinal frame pivotally connected to the cross-bar concentric with the arch and provided with a guide mounted upon a flange of the arch, seed-discharging mechanism, a 50 shaft or spindle mounted parallel with the longitudinal frame operatively connected with said seed-discharging mechanism, said shaft or spindle being provided contiguous to the pivotal point of the longitudinal frame 55 with a universal joint, a ground-wheel, and connections between the ground-wheel and the shaft or spindle, substantially as specified.

In testimony that I claim the foregoing as my own I have hereto affixed my signature in 60 the presence of two witnesses.

JAMES M. POORE.
